(74) *Attorney, Agent, or Firm* — Honigman Miller Schwartz and Cohn LLP; Andrew N. Weber; Jonathan P. O'Brien

(57) **CLAIM**

We claim the ornamental design for a hearing aid battery door, as shown and described.

DESCRIPTION

FIG. 1 is a left perspective view of a hearing aid battery door, showing our new design;

FIG. 2 is a left view of the hearing aid battery door of FIG. 1; FIG. 3 is a right view of the hearing aid battery door of FIG. 1;

FIG. 4 is a front view of the hearing aid battery door of FIG. 1;

FIG. 5 is a rear view of the hearing aid battery door of FIG. 1; FIG. 6 is a top view of the hearing aid battery door of FIG. 1; and,

FIG. 7 is a bottom view of the hearing aid battery door of FIG. 1.

The broken lines in the drawing views are directed to an environmental subject matter and form no part of the claimed design.

1 Claim, 5 Drawing Sheets
